UNITED STATES PATENT OFFICE.

EDGAR MAYETTE, OF CANISTEO, AND JOHN D. MITCHELL, OF HORNELL, NEW YORK;
SAID JOHN D. MITCHELL ASSIGNOR OF ONE-FOURTH OF THE WHOLE RIGHT TO
JOHN H. MITCHELL, OF HORNELL, NEW YORK.

BASKET.

1,105,205.

Specification of Letters Patent.

Patented July 28, 1914.

Application filed June 7, 1912. Serial No. 702,310.

To all whom it may concern:

Be it known that we, EDGAR MAYETTE and JOHN D. MITCHELL, citizens of the United States, residing, respectively, at Canisteo 5 and Hornell, in the county of Steuben, State of New York, have invented a new and useful Basket, of which the following is a specification.

This invention relates to improvements in 10 baskets.

The primary object of the invention is to provide a basket which is designed to be suspended by a strap or other hanger from the body of a person, the basket being of a configuration to conform to the curvature of 15 the person's trunk, means being provided for depositing the contents of the basket, without the necessity of tilting the basket.

A further object of the present invention 20 is to provide a basket having a hinged bottom, which can be readily released and allowed to swing upon its hinges in order to deposit the contents of the basket, the bottom being released from the edge of the 25 basket, remote from that edge to which the hanger or supporting device is attached, the releasing mechanism being disposed intermediate the ends of the basket.

With the foregoing and other objects in 30 view which will appear as the description proceeds, the invention resides in the combination and arrangement of parts and in the details of construction hereinafter described and claimed, it being understood that 35 changes in the precise embodiment of the invention herein disclosed can be made within the scope of what is claimed, without departing from the spirit of the invention.

In the drawings: Figure 1 is a perspective 40 view. Fig. 2 is a top plan view. Fig. 3 is a vertical section.

In the drawings, 10 designates the body of the basket which is tapered, forming a flared receiving end 11 and the substantially rectangular contracted delivery end 12, the wall 45 14 of the basket being concaved to conform to the curvature of the body of the wearer, a plurality of straps being attached to the curved wall adjacent the end of the same as 50 at 15, to which the band or supporting strap 16 is secured, this strap being placed over the shoulder, or placed to encircle the neck of the wearer.

The basket is designed for use in picking

fruit, it being noted that a basket of this 55 configuration allows the wearer to adjust the same so that it will fall in a convenient receiving position and when the person wearing the basket ascends a ladder the said basket may be swung around to his back. 60 The basket is also formed with rounded corners thus preventing the bruising of the fruit.

A bottom 17 is hingedly supported by the band 18 which embraces the lower end of 65 the basket, the bottom being disposed to contact with the band 18 when the same is in its closed position. A rim 19 embraces the upper end of the basket, a substantially U-shaped bracket 21 being secured 70 to each of the rims, the brackets being disposed in alignment and intermediate the ends of the basket. A rod 22 is embraced by said brackets, said rod being formed with the offset end 24 which, when the bottom is in closed position extends under the bottom wall of the same, holding said bottom against movement with respect to the basket. The terminal 25 of said rod is offset, to provide a handle by means of which 80 the same may be manipulated, that is, the offset portion 25 may be rotated to rotate the rod until the same releases the bottom 17, and after said bottom has been released and the fruit has been deposited within a 85 crate or other receptacle, the bottom may be brought into contact with the band 18 and the rod rotated by means of the offset 25 to bring the angularly disposed terminal 24 of the same beneath the bottom 17, the bottom being thus supported until the basket is again filled. Particular attention is called 90 to the peculiar arrangement of the rod 22 and it will be seen that the same may be easily manipulated by the wearer of the 95 basket when it is desired to release the bottom to deposit the fruit, the hand of the wearer normally resting on the rim 19 adjacent the offset terminal 25 of the rod 22. In this manner it will be noted that the 100 wearer need not change the position of his hand in releasing the bottom, the rod being rotated by the contact of the thumb with the offset terminal 25. After the contents of the basket has been deposited, the operator may move the bottom, until the same contacts with the rim 18 and rotate the rod until it assumes a position to retain the bot- 105

tom against movement with relation to the basket, either by manipulating the offset end 24 which engages the bottom of the basket, or by manipulating the offset end 25.

5 The many advantages of a construction of this character will be clearly apparent as it will be noted that while the bottom releasing and retaining mechanism is shown as applied to a particular form of basket, the 10 same may be attached to baskets already in use without altering the construction of the side wall, the basket being such as may be easily and economically manufactured.

It will be noted that the offsets 24 and 25 15 prevent the accidental displacement of the rod, said offset 25 contacting with the bracket secured to the band 19 and the offset 24 contacting with the bracket carried by the band 18, one end of the rod either being 20 bent after the same is applied to the basket, or the U-shaped brackets being attached to the basket while in contact with the rod.

What is claimed is:—

25 A basket including upper and lower rims, side walls disposed therebetween, a bottom hingedly secured to the lower rim, support-

ing means carried by the upper rim for the supporting of the basket, a pair of aligned bearings rigidly fixed to the upper and lower rims adjacent the front of the 30 poised basket and remote from the attachment of the securing means to the upper rim and the hinged connection of the bottom to the lower rim, a rod extending through said bearings provided with a 35 hook-shaped lower portion extending under and locking the bottom in a closed position with respect to the rim, the upper extremity of said rod bent oppositely with respect to the lower portion and at an angle to the top 40 of the basket and projecting thereabove, the said upper rod bend forming a handle for the releasing of the bottom, accessible from above the top of the basket.

In testimony that we claim the foregoing 45 as our own, we have hereto affixed our signatures in the presence of two witnesses.

EDGAR MAYETTE.
JOHN D. MITCHELL.
